CONTAINER AND METHOD OF MAKING SAME

Charles T. Walter, Chicago, Ill., assignor to Industrial Patents Corporation, Chicago, Ill., a corporation of Delaware

Application November 18, 1936, Serial No. 111,547

6 Claims. (Cl. 229—5.7)

This invention relates to containers and the method of making the same and more particularly to a container employing a metal ferrule in combination with fiber ends.

5 One of the objects of this invention is to provide an inexpensive serviceable container particularly adapted, for example, to such products as scouring powders and the like.

Another object of the invention is to provide a 10 metal ferrule for attachment to the end and side walls of fiber containers with a minimum metal waste.

Another object of the invention is to provide a 15 method for attaching toothed metal ferrules to fiber container ends.

Other objects of the invention will be apparent from the description and claims which follow.

The present invention is particularly directed to containers of the type described and claimed 20 in my Patent No. 1,959,971 entitled Container and method of making same.

Attention is called to the accompanying drawing in which similar characters of reference in the several figures indicate similar parts.

25 Figure 1 shows a portion of a strip of metal from which two ferrule blanks are to be prepared.

Figure 2 shows a blank bent in cylindrical shape, as upon a mandrel.

30 Figure 3 is a cross-sectional view of a single blank.

Figure 4 is a partial cross-sectional view showing a formed blank ready for attachment to a 35 fiber disk.

35 Figure 5 is a partial cross-sectional view of a container cover comprising a fiber disk and a metal ferrule in attached relationship.

Figure 6 is a plan view of the cover shown in 40 Figure 5.

Figure 7 is a top view of a container employing the novel cover.

Figure 8 is a partial cross-sectional view of a 45 container employing the novel cover of the present invention.

45 The first step in forming the ferrule is shown in Figure 1, wherein a thin strip of metal of sufficient width is stamped as shown, providing two ferrule blanks 1. The teeth and notches of these blanks may be complementary. The strips 50 are next cut into appropriate lengths and bent as upon a mandrel or otherwise, to the form shown in Figures 2 and 3.

The ferrule is then bent to the form shown in 55 Figure 4 providing a ring 2, a flange 3, and a plu-

rality of teeth 4 bent at right angles to the ring 2 and again bent as at 5, these teeth having points 6.

It will be noted by reference to Figure 4 that the tooth elements 4 are set at an angle to the axis of the ring 2. The preferred angle is about 5 20° to 25° as shown in the drawing.

The formed ferrule 1 is then attached to a fiber disk 7 by forcing the points 6 of the teeth into the surface of the fiber. The angle at which the points are bent causes a mushrooming effect, the 10 resistance of the plies of fiber causing the teeth to be bent backwardly upon themselves in the manner shown in Figure 5, firmly locking the metal ferrule to the fiber disk.

The resultant fiber disk is mechanically strong 15 and may be readily handled in a can machine to crimp the flange 3 upon the upper edge of container wall 8. The teeth or prongs 4, having been bent at right angles at their base, thence backwardly within the fiber disk with the points 20 passing into and being crimped within the fibrous end of the container, do not come into contact with product within the container.

I claim:

1. In a container, the combination of a body 25 formed of fibrous material, a ferrule shaped to conform to the body walls of the container, comprising a flange covering the ends of the body walls and crimped thereover and engaging the outer surfaces of said body walls, a vertical portion on the inside of said body walls, and a plurality of spaced prongs bent inwardly from said vertical portion, said prongs at their free ends having extending points bent downwardly and 30 backwardly and passed into and clenched wholly 35 within the body of a fibrous end.

2. The method of preparing a combination 40 fibrous and metal end for a container having fibrous side walls, which comprises stamping a ferrule blank from a flat sheet of metal, said blank being formed with one straight edge and one edge provided with a plurality of pointed prongs, forming the blank into the desired shape, flanging the straight edge outwardly and, the pronged edge inwardly, bending the prongs downwardly and backwardly intermediate their ends, inserting the backwardly bent point portions of the prongs in a fibrous blank end closure, causing said point portions of the prongs to remain within the body of the fibrous blank, and clenching 45 said point portions of the prongs within the fibrous blank.

3. A container comprising a fibrous body wall and a fibrous end secured to the fibrous body wall with a metallic ferrule provided with teeth 50

along one edge thereof and having a flange crimped over the edge of the fibrous body wall, the said teeth being clenched internally of the fibrous end, the points of said teeth being wholly within the body of said fibrous end.

4. The method of preparing a fibrous and metal end closure for a container which comprises forming a metallic ferrule provided with teeth along one edge thereof into the desired shape, bending the teeth at an angle, forcing the points of the teeth into the fibrous portion of the end closure and clenching the points of the teeth within the body of the fibrous portion of the end closure.

5. A container end comprising a fibrous portion and a metal ferrule, said metal ferrule provided with teeth along one edge thereof, said teeth

being clenched internally of the fibrous portion, the points of said teeth being entirely within said fibrous portion.

6. In combination with a fibrous end, a metallic ferrule adapted for securing the fibrous end to a container body, said ferrule comprising a body portion provided along one edge thereof with a plurality of pointed prongs, said prongs being flanged inwardly relative to said body portion and being bent downwardly and backwardly intermediate their ends at an angle relative to the inwardly flanged portion, the points of said prongs being passed into said fibrous end and clenched wholly within the body of the fibrous end.
